CLAIM

The ornamental design for a shoe upper, as shown and described.

DESCRIPTION

FIG. 1 is a front perspective view of a shoe upper showing my new design;

FIG. 2 is a side view thereof;

FIG. 3 is an opposite side view thereof; and,

FIG. 4 is a top view thereof.

The shaded area is claimed. The even-length broken lines within the shaded area represent an unclaimed feature. The uneven-length broken lines immediately adjacent to the shaded area represent unclaimed boundaries of the design. The uneven-length broken lines showing the remainder of the shoe represent unclaimed subject matter and form no part of the claimed design. The contrast in shading represents a contrast in appearance only and does not represent any particular color, material, texture or finish.
